UNITED STATES PATENT OFFICE

113,555

DESIGN FOR A TRACTOR

Nels E. Erickson, Minneapolis, Minn., assignor to Minneapolis-Moline Power Implement Company, Minneapolis, Minn., a corporation of Delaware

Application October 10, 1938, Serial No. 80,358

Term of patent 14 years

To all whom it may concern:

Be it known that I, Nels E. Erickson, a citizen of the United States and a resident of Minneapolis, in the county of Hennepin and State of Minnesota, have invented a new, original, and ornamental Design for a Tractor, of which the following is a specification, reference being had to the accompanying drawings, forming part thereof.

The left side of the tractor, not shown in the drawings, is substantially identical in appearance to the right side.

I claim:

The ornamental design for a tractor, as shown and described.

NELS E. ERICKSON.
